UNITED STATES PATENT OFFICE.

GEORGE WATSON, SR., OF BROOKFIELD, NOVA SCOTIA, CANADA.

MITER-BOX.

1,247,758.

Specification of Letters Patent. Patented Nov. 27, 1917.

Application filed August 8, 1917. Serial No. 185,139.

To all whom it may concern:

Be it known that I, GEORGE WATSON, Sr., a subject of the King of Great Britain, residing at Brookfield, in the county of Colchester, Prov. of N. S., Dominion of Canada, have invented certain new and useful Improvements in Miter-Boxes; and I do hereby declare the following to be a full, clear, and exact description of the invention, such as will enable others skilled in the art to which it appertains to make and use the same.

This invention relates to miter boxes, and has particular reference to adjustable miter box structures.

The object of the invention is to provide a practical miter box construction wherein a pair of swinging members move simultaneously to measure the same angle upon opposite sides of the line of cut, so that by a reversal of the material which is being cut, the abutting angle may be cut with absolute accuracy.

Furthermore, the invention contemplates the provision of a miter box which is foldable into a compact relation for transportation, so that it may be disposed in a workman's kit.

With the above objects in view, and such others relating to the details of construction, as may hereinafter appear, my invention will now be fully set forth and described, reference being had to the accompanying drawings.

35 In the drawings:—

Figure 1 is a plan view,

Fig. 2 is a rear elevation,

Fig. 3 is a section on line 3—3 of Fig. 1,

Fig. 4 is a front elevation of the device,

40 Fig. 5 is a bottom view, and

Fig. 6 is a section on line 6—6 of Fig. 4.

Referring more particularly to the drawings, 1 represents a base or support upon which the swinging tables 2 and 3 are mounted. The support 1 is an elongated casting whose ends terminate in circular portions, which I term tables 4 upon which the tables 2 and 3 are pivoted by means of the bolts 5. The outer ends of the tables 2 and 3 are provided with the feet 6. Slidable through a transverse slot 7 formed in the middle point of the base or support 1, is a saw supporting bar 8, which also terminates at its ends in the feet 9, which together with the feet 6 provide an adequate support for the entire structure. Also mounted

upon the bolts 5, below the tables 4, are the bars 10, the latter being secured to the bolts 5 at intermediate points, so that arms 11 extend inwardly therefrom, and the outer ends 60 of the bars 10 are secured to the bottoms of the tables 2 and 3 by means of a bolt 12 and 13 respectively. In order to properly support the bars 10 away from the bottoms of the tables 2 and 3 in suitable parallel and 65 spaced relation, washers 14 are provided upon the bolts 12 and 13.

A connecting bar or link 15 connects the tables 2 and 3, one end of the bar or link 15 being mounted upon the bolt 12, and the 70 opposite end of the bar having an elongated slot 16 which rides upon the bolt 13, a thumb nut 17 threaded on the bolt 13 provides a means for securing the tables in the various positions of adjustment at which the tables 75 may be set. A series of graduations 18 upon the bar or link 15 along the slot 16 are co-ordinated with the various angular positions of the tables. The inner ends of arms 11 of the bars 10 are pivotally connected to a pair 80 of links 19, whose opposite ends are revolute upon a common spindle 20 which extends downwardly from the forward end of the bar 8. As hereinbefore stated the bar 8 is slidable through the support 1, and by 85 reason of the connection provided through the links 19, when the tables 2 and 3 are swung with relation to the base 1, the bar is also moved with relation to the base. The ends of the bar 8 carry the saw-guides 21 90 and 22, said saw-guides including the slotted sleeves 23 which are slidable upon the correspondingly slotted standards 24, so that a miter saw will be properly supported, and limited in its cut. 95

The tables 2 and 3 are provided with the backs or flanges 25 along the rear edges, and through the flanges 25 are projected the clamping bolts 26 which co-operate with the stops 27 which rise from the tables, so that 100 material may be properly fastened for the sawing operations.

In the use of the above described instrument, it is possible to adjust the tables for any cut within the parts indicated in Fig. 105 4, and the simultaneous movement of the tables 2 and 3 by which they are always set to the same angle upon opposite sides of the line of cut, makes it possible to cut pieces for absolute fit, by cutting one upon one 110 table and one upon another.

Aside from the above defined advantages,

it will be apparent that the device is readily folded into a compact space so that it provides a satisfactory and convenient tool for use in a carpenter's kit.

5 What I claim as my invention is:—

1. A miter box comprising in combination, a base plate, saw tables upon the opposite ends of the base plate, bolts engaged through the saw tables and the base plate, arms engaged with the bolts below the base plate and projecting inwardly of the bolts, said arms being anchored to the saw tables, a member slidable through the base plate between the saw tables, links pivoted to the inwardly extending portions of the arms and with the slidable member near the rear end thereof, an adjusting bar connected with the arms

outwardly of the bolts, and saw supports carried near the ends of the slidable member. 20

2. A miter box, comprising in combination, a base plate, saw tables mounted upon the opposite ends of the base plate, inwardly extending arms carried by the saw tables, a member slidable through the base plate between the saw tables, links connecting the free ends of the arms to the rear end of the slidable member, an adjusting bar connecting the tables, and saw supports carried near the ends of the slidable member. 25 30

In testimony whereof, I affix my signature in the presence of two witnesses.

GEORGE WATSON, SR.
